US0D1108590S

(12) **United States Design Patent** (10) Patent No.: **US D1,108,590 S**
(45) Date of Patent: ** Jan. 6, 2026

(54) **REDUCING FLAT TOP DRAINAGE STRUCTURE**

(71) Applicant: **Advanced Drainage Systems, Inc.**, Hilliard, OH (US)

(72) Inventors: **Noah Hanley**, Stone Mountain, GA (US); **Courtney Ashliman**, Cumming, GA (US)

(73) Assignee: **Advanced Drainage Systems, Inc.**, Hilliard, OH (US)

(**) Term: **15 Years**

(21) Appl. No.: **29/911,626**

(22) Filed: **Sep. 6, 2023**

(51) LOC (15) Cl. **23-01**

(52) U.S. Cl.
